UNITED STATES PATENT OFFICE.

JOHN F. CRAWFORD, OF RACINE, WISCONSIN.

INTERNAL-COMBUSTION ENGINE.

1,255,862.

Specification of Letters Patent. Patented Feb. 12, 1918.

Application filed October 16, 1916. Serial No. 125,789.

To all whom it may concern:

Be it known that I, JOHN F. CRAWFORD, a citizen of the United States, and resident of Racine, in the county of Racine and State 5 of Wisconsin, have invented new and useful Improvements in Internal-Combustion Engines, of which the following is a description, reference being had to the accompanying drawings, which are a part of this 10 specification.

The invention relates to internal combustion engines.

The invention is designed more particularly to provide an internal combustion engine 15 of the sleeve valve type.

As in motors of the sleeve valve type, the present motor is designed to obviate the complicated puppet valve mechanism common in most types of engines and is also designed 20 to overcome the disadvantage of the reciprocating sleeve valve motors by providing a rotary sleeve which forms the inner working cylinder of motor and which is continuously turned to provide even wear on the 25 cylinder walls, pistons and piston rings.

The invention is further designed to provide a motor having a revolvable inner cylinder, also forming the valve, said cylinder having a tapered valve seat whereby the 30 working pressures of the engine will force the valve to its seat thereby sealing the chamber without the aid of packing rings and any wear on the valve will be taken up by reason of the taper fit.

35 The invention is further designed to provide an internal combustion engine in which all the valve mechanism is inclosed within the motor and actuated through a gearing connection with the crank shaft.

40 The invention further consists in the several features hereinafter set forth and more particularly defined by claims at the conclusion hereof.

In the drawings:

45 Figure 1 is a vertical sectional view through the motor;

Fig. 2 is a top view of the motor, parts being broken away and parts being shown in sections;

50 Fig. 3 is a detail sectional view taken on the line 3-3 of Fig. 2;

Fig. 4 is a section taken on the line 4-4 of Fig. 1;

55 Fig. 5 is a section taken on the line 5-5 of Fig. 1;

Fig. 6 is a section taken on the line 6-6 of Fig. 1.

The drawings show a single cylinder motor but it will be understood that the motor may have as many cylinders as desired. 60 The motor is also shown as of the four-cycle type but the sleeve valve shown and described may be used in two-cycle engines if desired.

In general the motor comprises an outer 65 cylinder 7, a rotary inner cylinder 8 also forming a valve, a piston 9 of usual construction working within the cylinder 8, a crank case 10 upon which the cylinders are mounted, a crank shaft 11 journaled in bearings 12 and 13 in the crank case, a pitman 9' of usual construction pivotally connected at its ends to the crank shaft 11 and piston 9 respectively, exhaust ports 14 and inlet ports 15 in the outer cylinder, and mechanism for operating the valve cylinder 8. 70

The outer cylinder 7 is provided with a water jacket 16 surrounding the inner walls 17 of said cylinder at the sides and top and also surrounding the valve ports thereby 80 providing an efficient cooling system for both the valve and the working cylinder.

A centrally disposed threaded opening 18' is located in the top of the cylinder to receive a spark plug. The cylinder is bored 85 to form cylindrical inner walls 17' forming the cylinder barrel and a frusto-conical inner wall 18 at the upper portion of the barrel forming a valve seat.

The inner cylinder 8 consists of a sleeve 90 having a hollow cylindrical barrel portion 19 fitting within the cylindrical bore 17 of the cylinder 7 and a hollow frusto-conical portion 20 fitting within the walls 18 of the cylinder 7 and adapted to seat against said 95 walls. This cylinder 8 and the top of the cylinder 7 form a tapered combustion chamber 21. The cylinder 8 is provided with a pair of oppositely disposed ports 22 adapted to be respectively brought into line with the 100 inlet and exhaust ports of the outer cylinder.

While during the operation of the engine the working pressures therein are sufficient to hold the inner cylinder to its seat means are provided for normally maintaining the 105 tapered head of the inner cylinder against the tapered valve seat of the outer cylinder. This means consists of annular bearing rings 23 which engage an annular flanged portion 24 on the outer side of the cylinder 8 and 110

which are yieldingly mounted on springs 25 interposed between them and an inwardly extending annular flange 26 on the crank case 10, the barrel of the cylinder 8 extending downwardly into the crank case as shown in Fig. 1.

As previously stated the inner revoluble cylinder 8 is also the valve for controlling the passage of combustible fuel to the combustion chamber and the passage of exhaust gases therefrom and suitable mechanism is provided for turning the sleeve to perform its valve functions during the operation of the engine. In the construction shown this mechanism is designed to run the sleeve at one-quarter engine speed and this will of course help in the proper lubrication of the running parts though the valve may be driven at any speed desired.

The sleeve operating mechanism consists of a gearing connection between the inner cylinder 8 and the crank shaft 11. This consists of a revoluble vertical shaft 27 journaled in the crank case and gearing connected between said shaft and the crank shaft 11 and between said shaft and the inner cylinder. The gearing connection between the shaft 27 and the crank shaft 11 comprises a worm wheel 28, mounted on the shaft 27 within the crank case, meshing with a worm 29 mounted on the crank shaft 11. Provision is made for taking up the end thrust on the shaft 27 by providing a roller bearing 30 disposed between the wheel 28 and a flange portion 31 of the crank case through which the shaft extends. The gearing connection between the shaft 27 and the cylinder 8 comprises a gear 32 mounted on the shaft 27, meshing with an idler gear 33 mounted on a short vertical shaft 34 journaled in the crank casing and meshing with a gear 35 formed integral with the cylinder 8 on the outside thereof near its lower end.

With the gearing construction above described the crank shaft 11 through the gearing and shaft 27 previously described continuously rotates the cylinder 8 in the same direction, the speed of rotation being dependent upon the ratio of the gears employed.

The engine shown being of the four-cycle type operates as follows: On the downward suction stroke of the piston 9, the cylinder 8 is in position with its ports 22 in line with inlet ports 15 in the outer cylinder 7 and the charge of combustible fuel is taken into the tapered combustion chamber 21 and on the compression stroke, the cylinder 8 is turned through the gearing connection with the crank shaft to close the ports and allow the piston 9 to compress the charge within the combustion chamber 21 after which the charge is fired, the cylinder 8 rotating during the firing stroke on the downward move-

ment of the piston and on the upward exhaust stroke of the piston the cylinder 8 has been rotated to bring its ports 22 in line with the exhaust ports 14 in the outer cylinder as shown in Fig. 1.

With the construction of inner and outer cylinders above described it will be observed that the tapered form of combustion chamber will serve to maintain the sleeve 8 upon its seat in the outer cylinder during the operation of the engine owing to working pressures in the combustion chamber exerting pressure against the tapered walls of the inner cylinder and it will also be noted that as the inner cylinder 8 is constantly revolving the wear between the outer and inner cylinders and that between the inner cylinder and the piston and piston rings will be evenly distributed.

It will also be noted that the mechanism for operating the sleeve valve is inclosed within the crank case and is of simple construction and positive in operation due to the gear drive.

It will further be noted that the construction of the engine is such as to produce quietness of operation, efficient cooling and ease in lubrication as the lubricant may be readily introduced between the outer and inner cylinders of the motor.

I am aware that the details of construction herein shown and described are capable of considerable variation without departing from the spirit of the invention and I therefore wish it to be understood that any construction coming within the scope of the following claims is within the scope of my invention.

What I claim as my invention is:

1. In an internal combustion engine, the combination of an outer cylinder having a bore therein consisting of a straight cylindrical portion and an inwardly tapered frusto-conoidal portion at its upper end, a hollow inner cylinder shaped to conform to the bore of the outer cylinder and having its upper open conoidal portion seated against the sides of said frusto-conoidal portion of the outer cylinder to form a combustion chamber, said outer cylinder being provided with inlet and exhaust ports, said inner cylinder having ports therein communicating with said combustion chamber and adapted to be brought into communication with said ports in the outer cylinder, a piston slidably mounted within the inner cylinder, a crank shaft operatively connected to said piston, and means for revolving said inner cylinder to control the passage of working fuel to and from the combustion chamber.

2. In an internal combustion engine, the combination of an outer cylinder having a bore therein consisting of a straight cylindrical portion and an inwardly tapered frusto-conoidal portion, a hollow inner cyl-

inder shaped to conform to the bore of the outer cylinder and having its upper open conoidal portion seated against the sides of said frusto-conoidal portion of the outer 5 cylinder to form a combustion chamber, said outer cylinder having ports in its tapered portion, said inner cylinder having ports in its tapered portion adapted to be brought into communication with the ports in the 10 outer cylinder, a piston working within the inner cylinder, a crank case having an inwardly extending flange, a crank shaft

mounted within said crank case and operatively connected to said piston, a flange on the inner cylinder, spring means interposed between the flange on the crank case and the flange on the cylinder to normally move said inner cylinder upwardly against its seat, and means for revolving said inner cylinder to control the passage of working 15 20 fuel to and from the combustion chamber.

In testimony whereof, I affix my signature.

JOHN F. CRAWFORD.
